(57) **CLAIM**

The ornamental design for an electronic atomizing device assembly as shown and described.

DESCRIPTION

FIG. 1 is a front, top, and right side perspective view of an electronic atomizing device assembly according to a first embodiment of our design where a first component and a second component are shown in an assembled state of use; FIG. 2 is a rear, bottom, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a front, top, and right side perspective view the electronic atomizing device assembly showing the first component removed from the assembly in FIGS. 1–8 for clarity of disclosure;

FIG. 10 is a rear, bottom, and left side perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is an enlarged top plan view thereof;

FIG. 16 is an enlarged bottom plan view thereof;

FIG. 17 is a front, top, and right side perspective view of the electronic atomizing device assembly showing the second component removed from the assembly in FIGS. 1–8 for clarity of disclosure;

(Continued)

FIG. 18 is a rear, bottom, and left side perspective view thereof;
 FIG. 19 is a front elevational view thereof;
 FIG. 20 is a rear elevational view thereof;
 FIG. 21 is a left side elevational view thereof;
 FIG. 22 is a right side elevational view thereof;
 FIG. 23 is an enlarged top plan view thereof;
 FIG. 24 is an enlarged bottom plan view thereof;
 FIG. 25 is a front, top, and right side perspective view of an electronic atomizing device assembly according to a second embodiment of our design where a first component and a second component are shown in an assembled state of use;
 FIG. 26 is a rear, bottom, and left side perspective view thereof;
 FIG. 27 is a front elevational view thereof;
 FIG. 28 is a rear elevational view thereof;
 FIG. 29 is a left side elevational view thereof;
 FIG. 30 is a right side elevational view thereof;
 FIG. 31 is an enlarged top plan view thereof;
 FIG. 32 is an enlarged bottom plan view thereof;
 FIG. 33 is a front, top, and right side perspective view of the electronic atomizing device assembly showing the first component removed from the assembly in FIGS. 25-32 for clarity of disclosure;
 FIG. 34 is a rear, bottom, and left side perspective view thereof;
 FIG. 35 is a front elevational view thereof;
 FIG. 36 is a rear elevational view thereof;
 FIG. 37 is a left side elevational view thereof;
 FIG. 38 is a right side elevational view thereof;
 FIG. 39 is an enlarged top plan view thereof;
 FIG. 40 is an enlarged bottom plan view thereof;
 FIG. 41 is a front, top, and right side perspective view of the electronic atomizing device assembly showing the second component removed from the assembly in FIGS. 25-32 for clarity of disclosure;
 FIG. 42 is a rear, bottom, and left side perspective view thereof;
 FIG. 43 is a front elevational view thereof;
 FIG. 44 is a rear elevational view thereof;
 FIG. 45 is a left side elevational view thereof;
 FIG. 46 is a right side elevational view thereof;
 FIG. 47 is an enlarged top plan view thereof; and,
 FIG. 48 is an enlarged bottom plan view thereof.

The broken lines in the drawings depict portions of the electronic atomizing device assembly that form no part of the claimed design.

The oblique shade lines in the drawings show transparency.
